UNITED STATES PATENT OFFICE.

CHARLES HAMMER, OF HOLLIS, NEW YORK, ASSIGNOR TO AMERICAN METAL CAP COMPANY, OF BROOKLYN, NEW YORK, A CORPORATION OF NEW YORK.

RESEALABLE METAL CAP.

Application filed July 29, 1926. Serial No. 125,647.

This invention relates to resealable caps or closures for containers, the object of the invention being to provide an improved cap adapted for use with containers having locking lugs or threads and a shoulder therebelow and particularly adapted for use with glass containers of the construction described.

A further object of the invention is the provision of an improved resealable cap having means for engaging projections or threads of the container to lock the cap on the rotation thereof and spaced integral means for engaging the shoulder of the container, the construction being such that the last holding means may be easily released without an unnecessary waste of time and labor and which cap is simple in construction, economical to manufacture and readily applied, and by means of which the container may be properly resealed by the user and by means of which also the purchaser may readily determine whether the contents have been tampered with.

Resealable caps as commonly constructed comprise a rotatable cap and a separable sealable band engaging the shoulder of the container all around the same. This sealing band usually overlaps the skirt of the cap so that this form of reseal closure necessitates the use of twice the amount of metal at the skirt of the cap which makes it expensive while the resealing band requires time and considerable labor to apply. The present improvement obviates the necessity of providing a separate sealing band, thereby reducing the quantity of metal required in the manufacture of such caps and consequently the expense of production. Furthermore in the ordinary reseal caps having a separable sealing band it is necessary to remove the band in order to release the cap and consequently the band can perform no function in the resealing of the container, whereas in the present improvement the shoulder holding portion, even after it has been released to permit the cap to be used by the purchaser, is in such position that it will, because of its resiliency, frictionally engage that shoulder and assist in holding the cap on the container even without the necessity of rotating the cap into position. Therefore, the present improved cap is not only more economical to manufacture but it has

certain advantages over the ordinary reseal cap.

In the drawings accompanying and forming a part of this specification, Fig. 1 is an inverted view of this improved cap. Fig. 2 illustrates a portion of the container and a partly sectional view of the cap applied thereto having one form of locking lug. Fig. 3 is a similar view to Fig. 2, but illustrating a different form of locking lug. Fig. 4 illustrates a similar construction to that shown in Figs. 2 and 3 but shows the cap with a different form of locking projection.

The container is shown in the present instance as a glass container 2, although this improved cap may be used with various forms of containers, and is provided with a plurality of locking threads 3 and spaced therebelow a shoulder 4. The cap in its preferred form comprises a top 5 and a depending flange or skirt 6 having at intervals therearound a plurality of depending skirt forming portions 7. The flange 6 of the cap is shown as relatively shallow with its lower edge spaced above the shoulder of the container as at 8, the purpose of which will be hereinafter explained. Located between and in alternation with the skirt portions 7 of the cap, the skirt 6 is provided with a plurality of inwardly extending locking projections. These may be of various forms.

In Fig. 2 these projections 9 are shown as of wedge shape or thread like form, the skirt being pressed inwardly to form these projections. In Fig. 3 these projections 10 are formed by slitting the metal of the skirt at the top of the projections and pressing the metal below the slit inwardly to form the projections; in Fig. 4, the projections 11 are formed at the lower edge of the skirt portion 6 by forcing or projecting the metal of the skirt inwardly without slitting the skirt. Any of these various forms of locking projections, as well as other forms thereof, may be used if desired, the several figures being merely intended to illustrate some of the different forms that may be used successfully.

Before explaining in detail the present improvement and mode of operation thereof, I desire to have it understood that the invention is not limited to the details of construction and arrangement of parts which are illustrated in the accompanying

drawings, since the invention is capable of other embodiments, and that the phraseology which I employ is for the purpose of description and not of limitation.

5 In the application of this improved cap to a container it is rotated to bring the locking lugs into engagement with the holding projections or threads of the container and then by suitable machinery the lower 10 edges of the depending skirt portions 7 are spun inwardly under the shoulder. In those cases where it is desired to vacuum seal the container, a suitable liner plate, gasket or other sealing means as 12, located at the 15 top of the cap may be used. When it is desired to remove the cap from the container, it is merely necessary to insert a sharp instrument, such as the prong of a fork, in the space 8 between the shoulder 20 and the lower edge of the skirt portion 6 of the cap, this space being provided especially for this purpose, whereupon a depending skirt portion 7 may be readily released and thereupon the cap may be quickly 25 rotated off the container. In resealing the cap, it is merely necessary to rotate the cap back into position on to the container. However in many instances, even this is 30 not required, as the mere application of the cap to the container without the rotation thereof will bring the depending skirt portions 7 into engagement with the shoulder of the container and owing to the resiliency thereof, the cap will be frictionally held in 35 place.

Thus, I have provided an improved reseal cap which, owing to the small amount of metal required for the manufacture thereof as compared with the ordinary reseal cap 40 requiring an annular band, can be economically manufactured at much less cost and which, moreover, can be used to reseal the container, being held thereon either by rotation or by friction, as desired.

45 In practice, the cap is provided with suitable corrugations which not only reinforce the skirt but facilitate the manufacture of the cap while at the same time they provide a roughened surface for more readily 50 rotating the cap into and out of position and in certain instances, if desired, the lower portions of the skirt proper may be beaded or strengthened and the lugs or projections formed therefrom or thereabove, as the case 55 may be.

In the form of cap shown it will be observed that the depending skirt forming portions 7 are of substantially the same width circumferentially as are those portions of the skirt proper between the depending portions so that the cap is not only symmetrical, but the depending portions 7 provide relatively long holding surfaces upon the shoulder of the container.

65 It is to be understood that by describing

in detail herein any particular form, structure or arrangement, it is not intended to limit the invention beyond the terms of the several claims or the requirements of the prior art.

Having thus explained the nature of my said invention and described a way of constructing and using the same, although without attempting to set forth all of the forms in which it may be made, or all of the 75 modes of its use, I claim:

1. A resealable metal cap comprising a top having a depending skirt provided at intervals with locking projections and intermediate such projections with dependent spaced skirt portions adapted to be inturned 80 under the shoulder of a container.

2. A resealable metal cap comprising a top having a depending skirt provided with locking projections and having below said 85 skirt a plurality of dependent spaced apart skirt forming portions adapted to be inturned under the shoulder of a container.

3. A resealable metal cap comprising a top having a depending skirt provided with locking projections and having below said 90 skirt a plurality of dependent spaced apart skirt forming portions of a width circumferentially substantially coinciding with the width of the skirt between said portions and adapted to be inturned under the shoulder of 95 the container.

4. A resealable metal cap comprising a top having a depending skirt provided at intervals with locking projections and intermediate such projections with dependent spaced skirt portions of a width circumferentially substantially coinciding with the width of those portions of the skirt between 100 said depending portions and adapted to be 105 inturned under the shoulder of a container.

5. The combination with a container, of a cap therefor having a skirt, means located at intervals on the skirt for attaching the cap to the container and a second attaching means integrally connected at intervals with said skirt and inoperative during the positioning or attaching of the cap by said first attaching means.

6. The combination with a container, of a 115 cap therefor, means for attaching the cap to the container and a second attaching means integrally connected with said first attaching means and inoperative during the positioning or attaching of the cap by said 120 first attaching means and spaced in alternation with said first attaching means.

7. The combination with a container of a cap therefor, means for attaching the cap to the container and a second attaching means 125 integrally connected with said first attaching means and inoperative during the positioning or attaching of the cap by said first attaching means and spaced to one side of said first attaching means.

8. The combination with a container, of a cap therefor, means for attaching the cap to the container and a second attaching means integrally connected with said first attaching means and inoperative during the positioning or attaching of the cap by said first attaching means and spaced to one side and below said first attaching means.

9. A package comprising a container having locking projections or threads and therebelow a shoulder, and a resealable cap comprising a top having a depending skirt provided with locking projections, the lower edge of said skirt terminating a spaced distance above the shoulder of the container for the insertion of a pointed instrument to release the cap, said skirt having at intervals depending skirt forming portions inturned under the shoulder of the container.

10. A package comprising a container having locking projections or threads and therebelow a shoulder, and a resealable cap comprising a top having a depending skirt provided with locking projections, the lower edge of said skirt terminating a spaced distance above the shoulder of the container for the insertion of a pointed instrument to release the cap, said skirt having at intervals depending skirt forming portions inturned under the shoulder of the container, said depending portions being located between the locking projections of the cap.

11. A package comprising a container having locking projections or threads and therebelow a shoulder, and a resealable cap comprising a top having a depending skirt provided with locking projections, the lower edge of said skirt terminating a spaced distance above the shoulder of the container for the insertion of a pointed instrument to release the cap, said skirt having at intervals depending skirt forming portions inturned under the shoulder of the container, said depending portions being located between the locking projections of the cap and having a width substantially coinciding circumferen-

tially with those portions of the skirt carrying the locking projections.

12. A resealable metal cap comprising a top having a depending skirt provided at intervals with impressed locking projections and intermediate such projections with dependent spaced resilient skirt portions adapted to frictionally engage the shoulder of a container and to be inturned thereunder. 55

13. A resealable metal cap comprising a top having a depending skirt provided at intervals with impressed locking projections and intermediate such projections with dependent spaced skirt portions adapted to engage the shoulder of a container and to be inturned thereunder, that portion of the skirt carrying the locking projections being spaced above the shoulder of the container to permit the insertion of an instrument to 65 release said dependent skirt portions.

14. A resealable metal cap for use with a container having holding projections or threads and a shoulder therebelow, and comprising a top having a depending shallow 70 skirt terminating a spaced distance above the shoulder and provided at intervals with impressed locking projections and at intervals with dependent spaced skirt portions adapted to overlap the shoulder and be in- 75 turned thereunder.

15. A resealable metal cap for use with a container having holding projections or threads and a shoulder therebelow, and comprising a top having a dependent shallow 80 skirt terminating a spaced distance above the shoulder and provided at intervals with impressed locking projections and at intervals with dependent spaced skirt portions adapted to overlap the shoulder and be in- 85 turned thereunder, said spaced skirt portions alternating with the locking projections.

Signed at Brooklyn, N. Y., this 26th day of July, 1926.

CHARLES HAMMER.
